(57) **CLAIM**

The ornamental design of a watch, as shown and described.

DESCRIPTION

FIG. 1 is a front elevational view of a watch showing my new design;

FIG. 2 is a back elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a front, right side perspective view thereof.

The broken line showing of the watch is included for the purpose of illustrating portions of the article and forms no part of the claimed design.
